ABSTRACT OF THE DISCLOSURE

In an analog multiplier, method and apparatus are disclosed for generating a voltage output signal having a segmental form approximating a parabolic or squared function of an input voltage signal. The input signal is shaped by a series of non-linear electrical conversion networks into a plurality of half wave triangular voltage signals having pre-selected frequency, amplitude and symmetry with the input voltage and thereafter all of the triangular voltage signals are electrically summated to produce the desired segmental parabolic or squared output signal.

The invention relates to electronic analog multipliers of a quarter-square type and more particularly to that portion of the apparatus which performs the squaring operation. An analog device as here used represents the output as a voltage.

The quarter-square type analog multiplier has as its basis of operation the algebraic relationship:

$$XY = \frac{1}{4} [(x+y)^2 - (x-y)^2]$$

The basic scheme of the quarter-square multiplier is shown in FIGURE 1 of the drawings. The principal parts of this type of multiplier are (1) one each summing and difference input networks for two-phase input signals which form the quantities $a(x+y)$ and $-a(x-y)$; (2) one each positive and negative absolute value networks which select only positive values of $a(x+y)$ and negative values of $-a(x-y)$; (3) one each positive and negative square law function generators to form the quantities $b(x+y)^2$ and $-b(x-y)^2$; and (4) an output summing unit which forms the desired output $b(x+y)^2 - b(x-y)^2 = cxy$.

Existing quarter-square multipliers generally employ passive diode function generators to perform the squaring operation. The major disadvantages of this method are temperature sensitivity, cumulative error caused by leakage current in the many diodes needed to achieve high accuracy, and the difficulty in adjusting the networks within the diode function generators to obtain the desired overall output curve characteristics because of the uncertainty of the individual diode switching characteristics.

An object of the present invention is to provide an active-type squaring network which to a very large degree eliminates the various errors associated with the diodes in the passive type squaring network and thus to obtain greater precision, accuracy and dependability.

Another object of the present invention is to provide an apparatus and method for producing the desired square-law function having the improved results above and to do so at a reasonable cost.

A further object of the present invention is to provide an apparatus and method for producing a square-law function of the character above and which will square any signal either DC or AC and do it substantially instantaneously whereby the apparatus will be able to constantly present the square of an input voltage which may vary rapidly with time; and which will automatically convert a negative input voltage to a positive squared output voltage in accordance with the algebraic principle that the square of a negative quantity is always a positive quantity.

2

The invention possesses other objects and features of advantage, some of which of the foregoing will be set forth in the following description of the preferred form of the invention which is illustrated in the drawings accompanying and forming part of this specification. It is to be understood, however, that variations in the showing made by the said drawings and description may be adopted within the scope of the invention as set forth in the claims.

Referring to said drawings:

FIGURE 1 is a schematic block diagram of a quarter-square analog multiplier.

FIGURE 2a is a graph showing one of the half-wave rectified triangular wave functions used in the present method and apparatus.

FIGURE 2b is a graph showing another of the triangular wave functions.

FIGURE 2c is a graph of another of the triangular wave functions.

FIGURE 2d is a graph of another of the triangular wave functions.

FIGURE 2e is a graph showing a segmental approximation of a parabolic function derived by summing the functions shown in FIGURES 2a, 2b, 2c and 2d.

FIGURE 3 is a graph showing an error curve function used in the present apparatus and method.

FIGURE 4 is a schematic block diagram showing essential portions of the apparatus and method used for generating and summing the particular wave form functions used in the present invention.

FIGURE 5 is a schematic diagram of a quarter-square electronic analog multiplier constructed in accordance with the present invention.

The analog multiplier is a device in which a voltage x and a voltage y are applied as inputs and from which a voltage cxy appears as output. Commonly these are 100 volt multipliers having a scale factor $c = -0.01$. It is usual for each x and y to vary as functions of time; and an important characteristic of a present multiplier is its ability to multiply faithfully when the x and the y inputs change rapidly in value.

With reference to FIGURE 1 the two input voltages x and y are applied to summing networks 11 and 12 and difference networks 13 and 14. Voltages representing minus x and minus y must be provided from a source external to the amplifier and these are likewise applied to the networks of 12, 13 and 14 as illustrated. The outputs of these networks as noted on FIGURE 1 are applied to absolute value networks 16 and 17 which provide outputs of $a|x+y|$ and $-a|x-y|$. These two outputs are then fed into squaring circuits 18 and 19, the outputs from which are represented by the products $b(x+y)^2$ and $-b(x-y)^2$. The latter outputs are then fed into a summing network 20 the output of which is the desired product cxy in accordance with well understood algebraic addition.

The present invention is directed to the squaring networks 18 and 19. In the quarter-square analog multiplier the input voltages to these squaring networks are $a|x+y|$ and $-a|x-y|$. For simplicity in the description that follows only one squaring circuit will be described and the input signal will be identified as S ; it being noted that reversed diodes in the lower squaring circuit 19 retain the negative sign of the signal being squared in that circuit. The generation of kS^2 will now be discussed.

In a squaring network an input voltage is converted to an output voltage which is the square of an input voltage multiplied by an appropriate constant. Ideally the relationship starts at zero so that if the input voltage is zero the output voltage is likewise zero so that a direct reading output is obtained without adjustment. If this curve were plotted, say on the face of an oscilloscope, with E_{in} as the abscissa and E_{out} as the ordinate, the

curve would appear as a parabola. In a larger sense, therefore, the function of the present invention is to provide electronically a parabolic function; and this is accomplished in accordance with the present invention by summing a plurality of symmetrical half wave rectified triangular wave functions, shown in FIGURE 2 as S_1 , S_2 , S_3 and S_4 , having a series relationship in which the successive functions have a frequency progression of 2^j and with the base break point of each triangular function coinciding with the peak of the next higher order series function. If we let p equal the number of these triangular waves as illustrated in FIGURES 2a, 2b, 2c and 2d, the summing of these triangular waves will produce a segmental curve as seen in FIGURE 2e having 2^p segments or break points. Finally in accordance with the present invention the successive peak magnitudes of the several triangular wave functions follow a relationship producing a change in slope in successive segments wherein the change in slope is a constant. The result is a segmental approximation of a parabolic function.

The foregoing may be seen graphically by an examination of FIGURES 2a, 2b, 2c, 2d and 2e. With reference to FIGURE 2a, it will be seen that the function S_4 is plotted as the ordinate and n as the abscissa and the latter has been subdivided for convenience into sixteen units. S_4 appears at $n=1$ as the beginning of an inclined ramp which extends to $n=2$ and then breaks downwardly to zero at $n=3$. In accordance with the "rectified" portion of the definition of this function, no signal appears between $n=3$ to $n=5$. At $n=5$ the function repeats as above and similarly repeats at $n=9$ and $n=13$. In other words if this were a full wave function there would be a negative portion of the curve appearing between $n=3-5$, $n=7-9$, and $n=11-13$. Because of the rectification, this negative portion of the function is removed. The peak amplitude of the function S_4 is set for purpose of this illustration at 1.

With reference to FIGURE 2b it will be seen that a similar symmetrical half wave rectified triangular wave function S_3 starts at zero value at $n=2$ and rises as a straight ramp to $n=4$ then extends downwardly to zero at $n=6$; and again repeats at $n=10$, with no signal appearing between $n=0-2$, $n=6-10$, and $n=14-16$. S_3 represents the next lower order function of the series relationship and accordingly there is a frequency progression between S_3 and S_4 of 2, that is in the present illustration S_3 has two half cycles and S_4 has four half cycles. It will also be seen that the base points viz $n=2, 6, 10$ and 14 of function S_3 coincide with the peaks of the next higher order series function S_4 . The peak magnitudes of function S_3 is set at 6.

With reference to FIGURE 2c it will be seen that the function S_2 is zero from $n=0$ to $n=4$, then rises on a ramp to $n=8$ and decreases in a similar ramp to zero at $n=12$ and remains at zero for the balance of the abscissa $n=12$ to $n=16$. This function S_2 follows the relationship above defined in that its frequency is one-half of the next higher order function S_3 ; and its base break points 4 and 12 coincide with the peaks of S_3 . The peak of function S_2 is set at 28.

With reference to FIGURE 2d it will be noted that function S_1 is zero from $n=0$ to $n=8$ then rises as a straight ramp to $n=16$. If the curve were continued the ramp would then start down so that function S_1 in common with functions S_2 , S_3 and S_4 is a symmetrical half wave rectified triangular wave function, only a portion of which is here used. It will also be observed that the frequency of S_1 is one-half of S_2 and the base break point of S_1 , viz., $n=8$ is located at the peak of the next higher order series function S_2 . The peak amplitude of S_1 is adjusted to 120.

As will be apparent from the foregoing, the slope of the successive curves S_1-S_4 decreases in the following order: 15, 7, 3 and 1. Thus viewing the slope progression in a reversed fashion, that is, reading from the higher to

the lower order functions, the slope of each successive wave form increases by powers of two. The summation of functions S_1 plus S_2 plus S_3 plus S_4 appears in FIGURE 2e. The relationship of these figures permits a graphic addition. From $n=0$ to $n=1$ all functions are zero and hence the summation shown in FIGURE 2e as segment 21 is likewise zero. From $n=1$ to $n=2$ the only function appearing is S_4 which has a slope of 1. Hence the next segment 22 of the summated function S is 1. Between $n=2$ to $n=3$ S_4 subtracts its slope of 1 from S_3 whose slope is 3 so that the next segment 23 has a slope of 2. Between $n=3$ to $n=4$ only function S_3 appears and accordingly the corresponding segment 24 will have a slope of 3. Between $n=4$ to $n=5$, function S_3 subtracts from function S_2 so that the resulting segment 25 has a slope of $7-3=4$. From $n=5$ to $n=6$, function S_4 is additive so that the resulting segment 26 has a slope of $7-3+1=5$. From $n=6$ to $n=7$ function S_4 subtracts from function S_2 so that the resulting segment 27 has a slope of $7-1=6$. From $n=7$ to $n=8$ only function S_2 is involved so that the corresponding segment 28 will have a slope of 7. Between $n=8$ and $n=9$ function S_2 subtracts from function S_1 so that the resulting segment 29 has a slope of $15-7=8$. Between $n=9$ and $n=10$ function S_4 is added in so that the resulting segment 30 has a slope of $15-7+1=9$. Between $n=10$ and $n=11$ function S_4 subtracts while function S_3 adds so that the slope of the resulting segment 31 is $15-7+3-1=10$. Between $n=11$ and $n=12$ function S_4 is at zero so that the resulting segment 32 has a slope of $15-7+3=11$. Between $n=12$ and $n=13$ function S_3 subtracts from function S_1 so that the resulting segment 33 has a slope of $15-3=12$. Between $n=13$ and $n=14$ function S_4 is added so that the resulting segment 34 has a slope of $15-3+1=13$. Between $n=14$ and $n=15$ function S_4 is subtracted from function S_1 so that the resulting segment 35 has a slope of $15-1=14$. Between $n=15$ and $n=16$ only function S_1 is involved so that the final segment 36 has a slope of 15.

The successive peaks or break points of the segments 21-36 will fall as seen in FIGURE 2e at 0, 1, 3, 6, 10, 15, 21, 28, 36, 45, 55, 66, 79, 91, 105, and 120.

For convenience in understanding the summation of a series of symmetrical half wave rectified triangular wave functions as above explained the analysis of each segment 21-36 is presented in the following table:

n	Segment	Individual Slopes				Summated	
		$S_1=15$	$S_2=7$	$S_3=3$	$S_4=1$	Slope	Peak Value
0-1	21	0	0	0	0	0	0
1-2	22	0	0	0	1	1	1
2-3	23	0	0	3	-1	2	3
3-4	24	0	0	3	0	3	6
4-5	25	0	7	-3	0	4	10
5-6	26	0	7	-3	1	5	15
6-7	27	0	7	0	-1	6	21
7-8	28	0	7	0	0	7	28
8-9	29	15	-7	0	0	8	36
9-10	30	15	-7	0	1	9	45
10-11	31	15	-7	3	-1	10	55
11-12	32	15	-7	3	0	11	66
12-13	33	15	0	-3	0	12	78
13-14	34	15	0	-3	1	13	91
14-15	35	15	0	0	-1	14	105
15-16	36	15	0	0	0	15	120

From the foregoing it will be apparent that the segmental approximation of a parabolic function illustrated in FIGURE 2e follows the general formula $S=\frac{1}{2}(n^2-n)$.

It can also be pointed out that the successive peak magnitudes of the several signals $S_1, S_2, S_3 \dots S_{j+1}$ will follow the following series relationship wherein j represents the series 0, 1, 2, 3

$$K_0, \frac{1}{2}K_0 \left[\frac{2^{j_{\max}}-2}{2^{j_{\max}}-1} \right], \frac{1}{6}K_0 \left[\frac{2^{j_{\max}}-2}{2^{j_{\max}}-1} \right]$$

$$\left[\frac{2^{j_{\max}} - 2}{2} \right], \dots, \frac{1}{4} K_0 \prod_{q=0}^{q=j} \left[\frac{2^{j_{\max}} - 2}{2^q} \right]$$

Where the first three terms represent the amplitudes of $S_1(j=0)$, $S_2(j=1)$, $S_3(j=2)$ respectively and the last term is a general formula defining the amplitude of the $S(j+1)^{\text{th}}$ triangular function for values of

$$j \geq 1$$

and where:

K_0 =an arbitrary constant describing the peak amplitude of $S_1(j=0)$

j =the number of the output from 0 to $j_{\max} - 1$

$j_{\max}$ =the total number of triangular signal functions used.

The present invention accordingly may be used whenever it is desired to generate a segmental approximation of a parabolic function having the generalized formula of $Ax^2 + Bx + C$. Where the invention is used for a quarter square multiplier a further refinement is desired viz. the elimination of the linear term Bx in the generalized formula or the term n in the formula of the curve shown in FIGURE 2e. This may be done by shifting the base break points of the several triangular wave functions S_1 , S_2 , S_3 and S_4 one-half of a unit of n to the left as of their positions seen in FIGURES 2a-2e.

In FIGURES 2a-2e, the horizontal coordinate or abscissa is represented by the variable n which in the present apparatus is the scaled input voltage. Once the number of triangular wave forms is selected and the number of segments or break points thus established, the units on n may be considered as the full-scale input voltage for which the system is designed, divided by the number of segments. In the illustration of FIGURES 2a-2e, four triangular wave forms are used thus producing a segmental parabolic curve having 2^4 or 16 segments. It is convenient to consider $n_{\max}$ to be the amount of input voltage which would correspond with the upper limit of the parabolic curve and which would be the maximum input voltage for which the system is designed. Conveniently, the input voltage range may be set at 100 volts and accordingly each unit of n in the illustration given would be 100 divided by 16.

It can be shown that by the step of shifting all of the triangular waves to the left by an amount of one-half unit, by adding a constant bias of minus one-half unit to the input signal n , the function becomes $S = \frac{1}{2}(n^2 - \frac{1}{4})$, as illustrated in dashed lines in FIGURE 2e.

Summarizing the foregoing and restating portions of the definition in some alternate terms for clarity it can be stated that the straight-line approximation of the parabolic function illustrated in FIGURE 2e is generated as the sum of a series of half-wave symmetrical triangular wave functions S_1 , S_2 , S_3 , S_4 , etc., having the following relationships:

(1) The number of cycles of each waveform is 2^{p-2} where p is the order of the waveform in the series.

(2) The horizontal shift from zero of each successive waveform, relative to the maximum span of the variable n , is $n_{\max}/2^p$.

(3) The slope of each successive waveform from the highest order down to S_1 changes according to increasing powers of 2, forming a sequence proportional to 1:3:7:15:31: etc. The relationship of the slopes is determined by the requirements that:

(a) the sum of the slopes at any value of n must be equal to the slope of the curve of the desired output function at the same value of n , and

(b) the slope of the function $\frac{1}{2}(n^2 - n)$ increases by a constant amount for each successive unit increment of n . In the straight-line approximation of the function, the significant unit increment of n is the constant value cor-

responding to the distance between breakpoints along the output curve which occur at the junctions of the straight-line segments.

Most importantly, in the foregoing it will be observed that the number of segments in the parabolic function, and hence the accuracy of the system, is greatly multiplied over the number of basic circuits or triangular wave forms used. Generally for p rectifying circuits providing p number of symmetrical half-wave rectified triangular wave functions, 2^p segments in the parabolic function is obtained.

As hereinabove noted, the accuracy of the square-law curve simulated by the foregoing method increases with the number of straight-line segments comprising the curve which in turn is dependent upon the number of component wave forms. Since the number of segments is equal to 2^p where p is the number of component wave forms, the method and apparatus of the present invention enables the production of a curve approximating a parabola to any degree of accuracy desired. From a practical standpoint 64 segments approach an optimum result since such a curve has a fine granular error which is within the tolerances of the electrical components used to generate the wave forms. For example the theoretical error with 64 sections is approximately 0.003 volt out of 100 volts full scale, which is 0.003 percent. In most analog devices, 0.01 percent is usually considered very good.

The generation of the triangular wave function is not as simple as doing a similar type job in a straight passive manner because as will be more fully hereinafter shown, it requires a number of feed-forward amplifiers and summing resistors for the several triangular wave functions. Assuming it is desired to generate the 64-section parabola, it would take six of these associated circuits. The last two or three of these circuits have quite a number of input resistors because all of the previous units sum into the later sections. Accordingly, it is a feature of the present invention that the last several triangular wave functions are replaced by a single special error correction wave function which may be obtained by a passive diode network. The present apparatus and method thus combines a basic output curve constructed of a relatively low number of triangular wave forms with an error correction curve to produce a final output curve consisting of a relatively large number of segments.

Examination of wave functions S_1 , S_2 , S_3 and S_4 in FIGURES 2a-2d shows that each successive wave form provides a correction to the function approximation generated by the sum of preceding wave forms. The true correction curve at any stage of the progression is equal to the difference of the continuous square-law function and the sum of the progression of triangular wave forms. This difference is itself a repetitive parabolic function.

As a feature of the present invention I have found that a satisfactory error curve may be generated by the fourth triangular wave function S_4 . To do so, wave form 54 is generated as a full wave as shown in solid line 42, in FIGURE 3 half wave rather than half wave, as is fed into a passive diode network to obtain the parabolic error curve 41.

Method of generating component triangular wave forms

A series of half-wave triangular wave forms which meets the requirements of the discussion relating to FIGURE 2 can be generated by the method illustrated in FIGURE 4. The first wave form of the series, S_{01} is generated by a signal summing-inverting-rectifying device N1. This device produces an output signal which is proportional to the input signal S_{in} representing the variable n . N1 may be defined as a non-linear function generating electric circuit having input and output relationships as follows:

if input $S > 0$, output = $-CS$

if input $S \leq 0$, output = 0

where C is a constant. A horizontal offset from the original signal shown in the box N1, is depicted in FIGURE 4a and is determined by the value of input bias signal SB1. This bias signal (opposite in polarity to S_{in}) holds the output of the device N1 at zero because of the rectifying characteristic until the absolute value of input signal exceeds it. The slope of the inverted output wave form S_{01} is controlled by the proportionality or gain characteristic of the device N1.

A second summing-rectifying-inverting device N2 is identical to N1 except that (1) the bias signal SB2 is half the value of SB1, (2) the slope of the output wave form S_{02} is set at half the value of the slope of S_{01} , and (3) the inverted output S_{01} is added to the summing input 43 of device N2. The resultant wave form is shown in FIGURE 4b.

With reference to FIGURE 4, it will be seen that signal S_{in} is fed to both the summing inputs 44 and 43 for circuits N1 and N2; and the output S_{01} is fed forwardly by conductor 46 to summing input 43 for circuit N2. Thus summing input 44 for the first circuit N1 has fed to it only the input signal S_{in} and the bias signal SB1. On the other hand summing input 43 for the second device N2 has fed to it not only the input signal S_{in} and its bias SB2, but also the output S_{01} of device N1. As a result the output wave form, shown in FIGURE 4b, has a horizontal offset controlled by bias SB2 and thereafter increases proportionately to the input S_{in} at one-half the rate of slope of the output S_{01} up to the value represented by bias SB1, at which point it decreases at the same rate because of the subtraction of output S_{01} at the input 43.

The next wave form S_{03} shown in FIGURE 4c is generated by device N3, and it will be observed that the summing input 47 for device N3 is connected to all of the preceding signals viz. S_{in} , S_{01} , and S_{02} as well as its own bias signal SB3. The derivation of output signal S_{04} shown in FIGURE 4d is obtained in a similar manner from device N4. The summing input 48 for device N4 is connected to all of the preceding signals, viz. S_{in} , S_{01} , S_{02} , and S_{03} as well as its own bias signal SB4.

As will be observed from the foregoing there is thus derived a series of symmetrical half-wave rectified triangular wave functions having the series relationship hereinabove defined. With reference to FIGURES 2a-e, it will be noted that the base break points of the several wave functions progress 1, 2, 4, 8, and that this indexing of the several functions is controlled by the feed forward and bias method depicted in FIGURE 4. The outputs S_{01} , S_{02} , S_{03} and S_{04} of the several devices, N1, N2, N3 and N4 may be fed to a summing output 57 to provide a segmental approximation of a parabolic (square-law) function; or device N4 may be adjusted to provide a full-wave output which then may be converted into an error curve function and then summated with outputs S_{01} , S_{02} and S_{03} as hereinabove described.

In accordance with the present invention the several devices N1, N2, N3 and N4 each include an electronic network centering about an operational amplifier (see operational amplifiers 1, 2, 3, 4, 5, 6, 7 and 8 in FIGURE 5). An operational amplifier is a direct coupled high gain amplifier of huge negative gain as indicated by the minus infinity sign inside the standard block envelope for the amplifier. Also characteristic of the use of such an amplifier because of its infinite gain, is of the large amount of feedback from output to input which normally is so large that the behavior of the circuit is described by the components feeding the amplifier and placed around it to provide the feedback. With reference to amplifier 1 in FIGURE 5 it will be noted that resistors R1, R2 and R3 are connected in the input to the amplifier and resistor R25 is connected in the feedback path. Also characteristic of the operational amplifier, the input is held at a virtual ground since even a very small input voltage will drive the amplifier to saturation. Accordingly, the gain is a function of the ratio of the input and feedback resistors. If these

are made equal the gain is minus 1 and if the ratio is changed to say 10, the gain would be minus 10. While the ideal operational amplifier has a gain of minus infinity, a commercial operational amplifier may have a gain of about 100,000 which for practical purposes is equivalent of infinite. For example, in such an amplifier one millivolt input will cause a full swing 100 volt output. Since operational amplifiers are well understood in the art further details of construction are not required to be given here and the usual block diagram as used in FIGURE 5 will suffice.

Summarizing in part the foregoing and with reference also to FIGURES 4 and 5 the input signal S_{in} for amplifier 1, see FIGURE 5, is applied to resistor R1 and to the input terminal 56. The output terminal 57 of the amplifier is connected to the input terminal 56 by a feedback loop including diode CR1 and resistor 25, the diode CR1 being connected to pass current only when the amplifier output is positive. Importantly also there is connected between the input and output terminals 56 and 57 a second feedback loop including diode CR2 which is connected to pass current only when the output terminal 57 is negative and block feedback when the output voltage at 57 is positive. The output terminal for the network is taken at point 58 in the first mentioned feedback loop between diode CR1 and resistor R25. Output voltage S_{01} (with reference also to FIGURE 4) appears at this point.

The operational amplifier and its network thus has (a) a conducting mode; and (b) a non-conducting mode. In 30 the conducting mode:

$$S_{01} = \frac{R25}{R1} \times S_{in}$$

In the non-conducting mode:

$$S_{01} = 0$$

Accordingly, when the input voltage S_{in} increases negatively, the output voltage S_{01} appears as a flat ramp as seen in FIGURES 4a and 2d; and when the input voltage S_{in} is positive, the output voltage S_{01} is zero, thus accomplishing the half-wave rectification hereinabove discussed.

With reference to FIGURE 5 and to operational amplifier 1, the linear ramp output S_{01} is shifted by reference voltage SB1. As will be observed a constant positive 100 volt reference voltage is provided at the terminal 61 of a voltage divider circuit including series connected resistors R19, R21, R22, R23, R24 and ground 62. For purposes of present illustration the bias voltage SB1 is set at +32 volts as derived from terminal 63 in the voltage divider circuit and resistor R2. Consequently, the diodes in the first circuit constrain the output S_{01} to zero except when the input signal is greater than -32 volts. In other words so long as the input signal S_{in} is positive no output voltage will appear. As S_{in} goes negative no output voltage will appear until S_{in} reaches and exceeds minus 32 volts. At that point the lineal ramp output S_{01} of FIGURES 2d and 4a will commence. As an important feature of the present invention this break point or corner is very sharp—much sharper than can be obtained with passive diode networks.

Operational amplifier 2 and its surrounding network is essentially similar to that described in connection with operational amplifier 1 with the following important changes:

65 (a) The bias voltage SB2 is reduced one-half so that the first break point of the triangular wave to be formed will be located at $n=4$ instead of $n=8$ as illustrated in FIGURES 2c and 2d; and

(b) The signal input and feedback resistors R4 and 70 R26 and the feed forward input resistor R5 are adjusted to provide relative slopes of $S_{in}=+1$ and $S_{02}=-2$.

As a result of the foregoing adjustments output signal S_{02} will remain at zero as the input signal goes negative to 16 volts and then will increase as a lineal ramp until 75 the input signal reaches minus 32 volts. At that point the

output signal S_{01} of the first circuit appears also at the input terminal 64 of the second circuit by reason of a forward connection made by conductor 66 which leads from output terminal 58 of the first circuit forwardly through resistor R5 to the input 64 of the second circuit. Resistor R5 adjusts the gain of output S_{01} to two times the gain of the second circuit. From this point on the voltage fed forward from the first circuit will increase at twice the rate as the voltage S_{in} applied to the second circuit and at opposite polarity because of the reversal in the polarity produced by operational amplifier 1. Accordingly, as the signal reaches minus 32 volts, corresponding with $n=8$ in FIGURE 2, the ramp turns down as seen at 67 in FIGURE 2c. When the output S_{02} has been driven down to zero by the forward fed signal S_{01} , diode CR3 holds the output at zero to the end of the scale, that is, between $n=12$ and $n=16$ as shown in FIGURES 2c.

Operational amplifier 3 and its network again is essentially similar to that shown in circuits 1 and 2 with the following modification: the bias voltage SB3 is again reduced one-half to eight volts so that the ramp of the output signal S_{03} of circuit number 3 will commence at $n=2$ instead of $n=4$ as shown in FIGURES 2b and 2c.

The output signals S_{01} and S_{02} of the first two circuits are both fed forward by conductors 66 and 68 and are applied through resistors R9 and R10 respectively to the input terminal 69 of operational amplifier 3.

As a result of the foregoing signal S_{03} will be zero as input signal S_{in} changes from zero to minus 8 (corresponding with $n=2$ in FIGURE 2b) and S_{03} will start up as a ramp as the input signal S_{in} goes from minus 8 to minus 16 (corresponding with $n=4$ in FIGURE 2b). At this point the output signal S_{02} from the second circuit is received at the input 69 of the third circuit and, as above explained, signal S_{02} increases at twice the rate and at reverse polarity as compared to the signal S_{in} of the third circuit. Accordingly, when the input signal S reaches minus 16 volts (the bias of the second circuit and corresponding with $n=4$) the output ramp S_{03} turns downwardly as seen at 71 in FIGURE 2b until it is driven to zero by signal S_{02} and it will remain at zero as signal S_{02} continues to increase to a point corresponding with $n=8$. At this point, signal S_{01} is impressed at the input terminal 69 of the third circuit through R9 with a relative slope of +2 and signal S_{02} reverses direction to a relative slope of -2, so that the net slope of these two feedforward signals is zero. The slope of the output signal S_{03} at point $n=8$, therefore, is determined solely by the input signal S_{in} with a relative slope of -1. The output S_{03} remains clamped at zero until the net sum of all three input voltages reaches zero potential at $n=10$. At this point, the output becomes positive and begins to rise positively from zero to a second peak value at $n=12$ as S_{in} increases. At $n=12$, the feedforward voltage S_{02} reaches zero so that the net input voltage, consisting of S_{in} with a relative slope of -1 and the feedforward voltage S_{01} with a relative slope of +2, causes the output voltage to reverse direction with a negative slope of -1. Voltage S_{03} decreases until it reaches a value of zero at $n=14$ and remains clamped at zero even though both S_{01} and S_{in} continue to increase to $n=16$.

Operational amplifier 4 and its network, which produce the full-wave triangular output used to drive the error-correction diode network, is similar to the circuits described for amplifiers 1 through 3 with the following exceptions:

(a) The signal input and feedback resistors R13 and R28 and the feedforward input resistors R14, R15, and R16 (for S_{01} , S_{02} , and S_{03} , respectively) are adjusted to produce relative slopes of $S_{in}=-1$, $S_{03}=-2$, $S_{02}=-2$, $S_{01}=-2$; and

(b) the rectifying circuitry, consisting of the clamping diodes in the feedback path of the amplifier, is eliminated so that a full wave output is produced; and

(c) the bias voltage SB4 is again reduced, but this

time to a smaller value than the four volts which might be expected for the fourth component waveform. Since the fourth amplifier generates the driving waveform for the error correction curve in order to represent, in this example, a six-component simulation of the parabolic curve, or $2^6=64$ segment curve, the initial bias of the fourth waveform would then be the same as for a hypothetical sixth waveform, or one volt ($\frac{1}{64}$ of the total range of 64 volts assumed for S_{in} in the present illustration).

As a result of the foregoing, the output signal S_{04} will be zero for values of S_{in} between zero and minus one volt (corresponding to $n=\frac{1}{4}$). That is, bias voltage SB4 is selected to adjust S_{04} to approach a full waveform shown by solid line 42 in FIGURE 3, for the generation of parabolic error curve 41. When $S_{in}=-1$ volt, the negative input signal overtakes the positive one volt bias and the output S_{04} begins to increase linearly with a relative slope of +1 as S_{in} is further increased. When S_{in} equals -8 volts at $n=2$, the output voltage S_{03} which commences at that point, is fed forward through conductor 73 and resistor R16 with a relative slope of -2, causing the output S_{04} to change directions and decrease with a relative slope of minus 1. S_{04} has a value of zero volts at $n=4$. At this point, the feedforward voltage S_{03} changes to a relative slope of +2 but its effect is cancelled out by the feedforward voltage S_{02} which commences at that point with a slope of -2. As a result, output S_{04} is determined only by the input signal S_{in} which causes it to increase to a second positive peak at $n=6$. At this point, the feedforward voltage S_{03} drops out and the remaining feedforward voltage S_{02} , with a relative negative slope of -2, causes the output S_{04} to reverse again until it reaches a value of zero at $n=6$. The remaining two cycles of S_{04} are generated in a similar manner by the alternations of the feedforward voltages S_{03} , S_{02} , and S_{01} which commence at the point $n=8$.

Bias correction

Up to this point in the discussion of the generation of the triangular waveforms S_{01} , S_{02} , S_{03} and S_{04} , the special bias of one-half unit necessary to convert the general parabolic curve $F(n)=\frac{1}{2}(n^2-n)$ to the square-law function $F(n+\frac{1}{2})=\frac{1}{2}(n_0^2-\frac{1}{4})$ has been disregarded. Since it is desired to shift the overall curve one-half unit to the left to accomplish the desired transformation, this may be done by shifting each component waveform one-half unit to the left by reducing the positive bias. In the 64-segment approximation, with a 64 volt range of input, as in the present example, a unit is defined as 64 volts total range of input divided by 64 segments, or one volt, which is equal to $n=\frac{1}{4}$ with reference to FIGURES 2 and 3. Therefore, a negative bias of $n=\frac{1}{2} \times \frac{1}{4}=\frac{1}{8}$ must be added to each waveform so that $SB1=7\frac{1}{8}$ units (+31½ volts), $SB2=3\frac{3}{8}$ units (15½ volts), $SB3=1\frac{1}{8}$ units (+7½ volts), and $SB4=\frac{1}{8}$ unit (+½ volt).

The error correction curve, FIGURE 3, is generated by a conventional function generator of the passive diode network type, represented by blocks +D and -D in FIGURE 5. With reference to block +D, it will be seen that the output S_{04} of circuit number 4 is applied to the input terminal of the passive diode network made up of seven sections 77, 78, 79, 80, 81, 82 and 83, each consisting of a resistor and diode as illustrated. These sections are connected at spaced voltage points to a voltage divider 84 connected at one end to input terminal 76 and at its other end to a reference voltage as for example minus 100 volts as here shown. The several sections 77-83 are connected to a common output terminal 86.

As an important feature of the present passive diode network, an eight segment square-law wave form is generated by a seven-branch network for each half cycle or full excursion of the input triangular wave form. This is true since the first diode path does not conduct at the zero input level. Since the passive network provides an eight section segmental approximation of a parabolic function,

11

it serves in effect to add three additional circuits of the type of circuits 1, 2 and 3 hereinabove described. The result is the provision of a segmental approximation of a parabolic function having 64 sections which approaches the optimum square-law function.

It is possible to make a fairly accurate sixteen section passive network. With such a sixteen section network it would not be necessary to come down to the fourth amplifier. One could use the third amplifier converted to full wave as above discussed and drive the sixteen section passive network with two peaks; and summate the result with the first two amplifiers in the manner herein described, and still get a 64 section segmental approximation of the desired parabolic function.

Description of overall apparatus

The overall schematic diagram of the quarter-square electronic analog multiplier is illustrated in FIGURE 5. The primary input circuitry is the same as that for existing quarter-square multipliers. The two input signals X and Y are applied simultaneously as two-phase signals (+X and -X, +Y and -Y) to the positive input summing and absolute value network (Block +A) and a negative input summing and absolute value network (Block -A). The output of the network +A is a positive quantity $X - Y$ regardless of the polarities of the individual quantities X and Y. Similarly, the output of network -A is always a negative quantity $-(X + Y)$.

These inputs are applied to an active positive or negative squaring network (Block +B or -B). Each active network functions electrically in accordance with the description applicable to FIGURE 4. With reference to the positive squaring network (Block +B), the junction of resistors R1, R2, and R3 is equivalent to summing point S₁ in FIGURE 4. The negative signal $-(X + Y)$ from input block -A is equivalent to the common input signal S_{in} and is applied to all four stages of the active network through R1, R4, R8, and R13. The bias signals corresponding to SB1, SB2, etc. In FIGURE 4 are derived from a positive voltage divider (R19 through R24) and are applied to all four stages of the active squaring network through R2, R6, R11, and R17. The "feedforward" connection from the output of one stage to the input of each successive stage is accomplished from stage 1 through R5, R9, and R14, from stage 2 through R10 and R15, and from stage 3 through R16.

An additional input is applied to each stage through R3, R7, R12 and R18 for diode compensation as discussed below.

Summary of function of the active squaring network stage

With reference to FIGURE 5, amplifier No. 1 with the immediately connected passive components, functions as the generator N1 of triangular waveform S₀₁ in the description applicable to FIGURE 4. Amplifier 1 characteristically inverts the output signal polarity with respect to the input polarity. Rectifier CR2 holds the output signal level at zero as long as the sum of input signals has a positive polarity. Rectifier CR1 switches in the amplifier feedback component R25 to initiate the normal summing function whenever the sum of input signals has a negative polarity. The action of these two elements provide the rectifying and biasing requirements for the stage. The gain of the stage, which determines the slope of the output signal relative to the input signal is controlled by the basic relationship of DC amplifier operation: gain = the ratio of feedback resistance to the individual input resistance. Two separate requirements for the slope of the individual waveforms were previously described: (1) to generate a series of triangular waveforms, the first waveforms in the series must be "fed-forward" to the successive waveform-generating units with a specific slope relationship, and (2) the complete series of individual waveforms must be given a different slope relationship and added together to produce the overall function curve.

12

Requirement (1) is fulfilled by the amplifier gain determined by the input resistors of amplifiers 1 through 4 (Block +B) or amplifiers 5 through 8 (Block -B). Requirement (2) is met by the gain determined by the input resistors of the output summing amplifier 9.

Diode compensation at the input

One source of error in the conventional input network (Block A or -A) is the finite impedance of the diodes in the absolute value circuit and their non-linear operating characteristics. The voltage drop across these diodes may be treated as an error signal opposite in polarity to the desired input signal. To compensate for this undesirable signal, a voltage of equal amplitude is developed across the diode CR3 in the diode compensation network (Block C or -C). This voltage is added into the summing junction of the following amplifiers to cancel out the error voltage created across the diodes in Block A or -A.

The output terminals 58, 89, 90 and 86 of the first three operational amplifier stages and the passive squaring network stage are connected through resistors R31, R32, R33 and R34 to a common output terminal 92. In a like manner the outputs of operational amplifiers 5, 6 and 7 shown in Block -B and the output of passive squaring network No. II shown in Block -D are connected to a common output terminal 93. The two outputs of the two systems are connected from terminals 92 and 93 to the input terminal 94 of operational amplifier 9. The product KXY, K being a constant, appears at the output 96 of operational amplifier 9.

I claim:

1. The method of generating from a time variable input signal an output signal having 2^p linear segments defining a segmental approximation of a parabolic function of the input signal which comprises, forming the input signal into a plurality (p) of symmetrical half wave rectified triangular wave signals having a series relationship in which successive triangular signals have a frequency progression of 2^j where j represents the series 0, 1, 2, 3 . . . $p-1$ and with the base break points of each triangular signal coinciding with the peaks of the next higher order frequency signal, and summing said triangular signals and adjusting the peak magnitudes thereof to selected values producing said segmental output signal having a constant change in slope between successive segments.

2. The method of squaring a time variable quantity which comprises, representing the quantity to be squared as the magnitude of a time variable electrical input signal, forming the input signal into a series of symmetrical half wave rectified triangular wave signals having a frequency progression of 2^j where j represents the series 0, 1, 2, 3 . . . and with the base break points coinciding with the peaks of the next higher order frequency signal, summing said triangular signals to produce a segmental wave form, adjusting the successive peak magnitudes of said triangular wave signals to produce a change in slope in successive segments of said segmental wave form wherein said change in slope is a constant approximating a parabolic wave form having the general formula Ax^2 plus Bx plus C , and biasing the base break points of said triangular wave signals with respect to the input signal to eliminate the factor Bx .

3. The method of squaring a time variable quantity which comprises, representing the quantity to be squared as a time variable voltage, impressing said voltage as an input to an electronic network having a plurality (p) of voltage outputs all being functions of said input voltage and being a series of symmetrical half wave rectified triangular signals having a frequency progression of 2^j and with the base break points of each triangular signal coinciding with the peaks of the next higher order frequency signal, summing said outputs, and adjusting the successive peak magnitudes of said triangular signals to

produce a segmental parabolic voltage function having 2^p segments and having a constant change in slope between successive segments.

4. The method of squaring a time variable quantity which comprises, representing the quantity to be squared as a time variable voltage signal, forming said voltage signal into a series of symmetrical half wave rectified triangular wave signals having a frequency progression of 2^j where j represents the series 0, 1, 2, 3 . . . and successive peak magnitudes of:

$$K_0, \frac{1}{4}K_0 \left[\frac{2^{j_{\max}} - 2}{2^{j_{\max}} - 1} \right], \frac{1}{16}K_0 \left[\frac{2^{j_{\max}} - 2}{2^{j_{\max}} - 1} \right]$$

$$\left[\frac{2^{j_{\max}} - 2}{2} \right], \dots, \frac{1}{4^j}K_0 \prod_{q=0}^{q=j-1} \left[\frac{2^{j_{\max}} - 2}{2^q - 1} \right]$$

where the first three terms of the series represent the amplitudes of the triangular signals for j equals 0, j equals 1, j equals 2 respectively and last term is a general formula defining the amplitude of the jth triangular signal for values $1 \leq j \leq j_{\max} - 1$.

and where:

K_0 equals an arbitrary constant describing the peak amplitude of the triangular signal for j equals 0,

$j_{\max}$ equals the total number of triangular signals used.

and with the base break points of each triangular signals coinciding with the peaks of the next higher order frequency triangular signal and summatting said triangular signals.

5. An apparatus for squaring a time variable quantity represented by a time variable input voltage signal comprising, a non-linear electronic network having an input adapted to receive such voltage signal and having a plurality (p) of outputs producing as a function of the input voltage signal a series of symmetrical half wave rectified triangular wave signals having a frequency progression of 2^j where j represents the series 0, 1, 2, 3 and with the base break points of each triangular signal coinciding with the peaks of the next higher order frequency triangular signal and means connected to said outputs summing said triangular signals and adjusting the successive peak magnitudes of said triangular signals to produce a segmental parabolic function having 2^p segments having a constant change in slope between successive segments.

6. An apparatus as defined in claim 5 wherein said electronic network includes a plurality of operational amplifiers having feedback diodes connected in the circuit thereof providing said non-linear electrical characteristics of said network.

7. An apparatus for squaring a time variable quantity represented by the amplitude of a time variable input voltage signal comprising; an electronic network having an input adapted for connection to the voltage signal, a plurality of operational amplifiers each having a resistive diode feedback circuit providing an output, and input resistors connected to receive the input signal and being connected to the outputs of certain other said amplifiers providing at said outputs a series of symmetrical half wave rectified triangular wave signals having a frequency progression of 2^j where j represents the series 0, 1, 2, 3 . . . , and with the base break points of each triangular signal coinciding with the peaks of the next higher frequency signal; a passive diode squaring network having an output; and means summatting the signals appearing at said squaring network output and said electronic network outputs except the highest frequency signal output thereof and adjusting the magnitudes of the summated output signals to produce a segmental parabolic function having a constant change in slope between successive segments.

8. An apparatus for generating an output signal as a

75

segmental approximated parabolic function of a time variable input signal comprising, an electric summing circuit each having a plurality of inputs and an output equal to the summation of said inputs, a plurality of non-linear function generating electric circuits each having input and output relationships as follows:

if input $S > 0$, output equals $-CS$

if input $S \leq 0$, output equals 0

10 where S is an electrical signal and C is a constant, the output of each summatting circuit being individually connected to the input of a separate non-linear circuit providing a plurality of associated circuits, said associated circuits being arranged to provide an inter-connected series thereof in which the non-linear circuit output of each associated circuit is connected to one of the summing circuit inputs of all succeeding associated circuits of the series, another of the inputs of each summing circuit being connected to receive the input signal, biasing means being connected one to an input of each of said summing circuits providing biasing signals thereto progressively decreasing in magnitude by a factor of $\frac{1}{2}$ in each successive associated circuit of the series, and a summing circuit connected to the outputs of all of the non-linear circuits, whereby said circuits co-function with the aforesaid constant C providing the output signal as a plurality of continuous electrical segments having a constant change in slope between successive segments.

9. An apparatus as defined in claim 8 wherein each of said associated circuits comprise, an operational amplifier having a feedback network consisting of a serially connected resistor and diode providing a first feedback path and a diode oppositely poled with respect to said first named diode providing a second feedback path.

10. An apparatus for generating a segmental voltage signal approximation of a parabolic function in response to a time variable input voltage signal comprising, a plurality of electric summing circuits each having a plurality of inputs and an output equal to the summation of said inputs, a plurality of non-linear function generating electric circuits each having input and output relationships as follows:

if input $S > 0$, output equals $-CS$

if input $S \leq 0$, output equals 0

45 where S is a voltage signal and C is a constant, the output of each summing circuit being individually connected to the input of a separate non-linear circuit providing a plurality of n associated circuits, said n associated circuits being arranged to provide an interconnected series thereof defined by the non-linear circuit output of each associated circuit being connected to one of the summing circuit inputs of all succeeding associated circuits of the series, one of the inputs of each summing circuit being connected to receive the input signal, a plurality of fixed voltage biasing means being connected one to an input of each said summing circuits except that of the nth associated circuit of the series, a passive diode squaring network having an input and an output with the input connected to the non-linear circuit output of the nth associated circuit, and a summing circuit connected to the output of said passive network and the non-linear circuit outputs of all of the associated circuits except that of said n^{th} associated circuit, whereby said circuits co-function with the aforesaid constant C to provide the segmental voltage signal consisting of a plurality of continuous electrical segments having a constant change in slope between successive segments.

11. The method of generating an electrical output signal having a parabolic relationship with a time variable electrical input signal which comprises, shaping the input signal into a plurality (p) of symmetrical half wave rectified triangular wave signals having a series relationship in which the successive signals have a frequency progression of 2^j where j represents the series 0, 1, 2, 3 . . . $p-1$ and

with the base break points of each triangular signal coinciding with the peaks of the next higher frequency signal and summatting the triangular signals with successive peak magnitudes following a relationship defining a segmental parabolic electrical signal having a constant change in slope between successive segments and generating a segmental electrical signal approximating the error deviation of said segmental parabolic electrical signal from a parabola, and summatting said error signal and said segmental parabolic signal to produce the output signal.

12. The method defined in claim 11 wherein a series of n triangular signals are provided and the nth signal is shaped to provide said segmental error signal.

13. The method of squaring a time variable quantity which comprises, representing the quantity to be squared as the amplitude of a time variable and voltage signal and impressing said voltage signal as an input to an electronic network having a plurality (p) of voltage outputs all being functions of said input voltage and being a series of symmetrical half wave rectified triangular signals having a frequency progression of 2^j and with the base break points of each triangular signal coinciding with the peaks of the

5

10

20

next higher frequency triangular signal and summatting said outputs except the highest order signal output and adjusting the successive peak magnitudes of the summatted triangular signals to produce a segmental parabolic voltage function having 2^{p-1} segments, applying said highest order frequency signal output to a passive diode squaring network to generate an error wave voltage approximating the error deviation of said segmental parabolic function from a parabola, and summatting said error wave voltage and said segmental parabolic function.
